UNITED STATES PATENT OFFICE.

OVERTON WINSTON, OF MINNEAPOLIS, MINNESOTA.

HEADLIGHT.

1,240,282.

Specification of Letters Patent. Patented Sept. 18, 1917.

Application filed December 2, 1915. Serial No. 64,662.

To all whom it may concern:

Be it known that I, OVERTON WINSTON, a citizen of the United States, residing at Minneapolis, in the county of Hennepin 5 and State of Minnesota, have invented certain new and useful Improvements in Headlights; and I do hereby declare the following to be a full, clear, and exact description of the invention, such as will enable others 10 skilled in the art to which it appertains to make and use the same.

My present invention relates to electric headlights for automobiles and other vehicles, and is in the nature of the modification 15 of, or improvement on, the headlight disclosed and claimed in the companion application executed by me of even date herewith, and entitled "Headlights," S. N. 64,661, filed of date, December 2nd, 1915.

Generally stated, the invention consists of 20 the novel devices and combinations of devices hereinafter described and defined in the claims.

Particularly, the invention is directed to 25 improved means for shifting the light bulb in respect to the axis of the reflector, but involves other minor but important features of construction.

In the accompanying drawings which 30 illustrate the invention, like characters indicate like parts throughout the several views.

Referring to the drawings:

Figure 1 is a view chiefly in vertical section with some parts in full, showing a 35 headlight embodying my invention.

Fig. 2 is a view chiefly in elevation but with some parts in full, showing one of the 40 latch devices and certain coöperating ele- ments;

Fig. 3 is a section on the line x^3-x^3 of Fig. 2;

Fig. 4 is a horizontal section taken ap- 45 proximately on the line x^4-x^4 of Fig. 1; and

Fig. 5 is a section on the line x^5-x^5 of Fig. 4.

The numeral 1 indicates the casing of an 50 ordinary headlight, such as used on automobiles, and the numerals 2 and 3, respectively, indicate the reflector and the lens of the glass plate of the headlight. The reflector 2, instead of being rigid, in respect to the casing, is connected thereto at the front 55 edge of its marginal rim, by diametrically

opposite horizontal pivots 2^a. The electric light bulb 4 illustrated in the drawings is held in a socket of novel construction, the details of which are not herein fully illustrated, but are fully disclosed and claimed 60 in my said companion application. For the purposes of this case, it is desirable, only, to particularly note the sleeve 5 of the bulb which is telescoped into the collar 7, which, in turn, is mounted in the end of the inner member 9 of a pair of telescoped tubular channels, the outer member 8 of which is provided in its rear end with a swiveled lamp adjusting nut 13, by rotation of which latter the lamp may be adjusted longitudinally of the axis of the reflector. The numeral 21 indicates a spring-pressed screw driver mounted in and extended through the back of the casing 1 and adapted to be pressed inward into engagement with radial 75 grooves formed in the rear end of the nut 13. The said parts 4 to 21, inclusive, just above noted, bear the same numerals in my said companion application and the details of construction and operation thereof may 80 be had by reference to the said application.

The front end of the outer shell 8 of the lamp socket in this instance is, however, ex- 85 tended into an axial opening of the reflector and is pivotally connected to the reflector, by horizontally alined pivot screws 22 seated in a ring 23. This ring 23 is tapered and fits within a flaring annular flange 24 on the back of the reflector. A split clamping 90 ring 25 held together by short nut-equipped bolts 26 secures the ring 23 to the said flange 24. The intermediate portion of the outer shell 8 is seated in an annular fulcrum 27^a that has threaded engagement with a sur- 95 rounding tubular bearing 27 rigidly attached to the back of the casing 1 and axially alined therewith. The annular fulcrum 27^a has a cylindrical body 28 that is telescoped over a cylindrical head 29, the reduced tubular stem of which is journaled in the hub 100 of the bearing 27 and affords a seat for the screw driver 21. To the outer end of the reduced stem of the said head 29 is secured a knurled flange 30, by means of which the said member 29 may be easily rotated.

The cylindrical body 28 of the annular fulcrum 27^a is provided with lugs 31 that engage longitudinal slots 32 formed in the said head 29, so that the said members 28 and 29 are caused to partake of a common rota- 110

tion. The member 29, however, is held against axial movement while the fulcrum member 27^a is capable of axial traveling movement produced when rotated by its 5 screw-threaded engagement with the tubular bearing 27. The numeral 33 indicates a cap shown as applied to the outer end hub of the bearing 27, and which, when removed, affords access both to the head of the screw 10 driver and to the finger piece 30 of the rotary head 29.

Obviously, by the rotation of the head 29 the annular fulcrum 27^a may be moved forwardly or rearwardly on the outer shell 8 15 of the lamp socket. Also, it will be understood that by forcing the screw driver inward and then rotating the same, the lamp may be adjusted longitudinally of the axis of the reflector.

20 The reflector has a rigidly attached arm 34 which projects rearward within the casing 1 and is connected by a slot and pin coupling 35, to the intermediate portion of an endwise movable plunger or magnetic 25 core 36, preferably made of soft iron. This plunger 36 works axially through a pair of solenoids 37 controlled by suitable electric connections, not shown, attached to shelf-like projections 38 of the tubular bearing 27.

30 To the ends of the plunger 36 are rigidly attached by brazing, or otherwise, brass extensions that have screw-threaded engagement with the interiors of the tubular latch heads 39 that are seated for endwise movements 35 in brass bearing rings 41, shown as secured to the respective solenoids 37. These latch heads 39 are provided with stems 42 that extend freely through passages in the casing 1 and are provided outside 40 thereof with operating knobs or heads 43 formed with longitudinal peripheral grooves or corrugations engaged by spring fingers 44 attached to hubs 45 secured on the said casing 1. The numeral 45^a indicates 45 caps detachably applied to the hubs 45 and normally including said parts 43 and 44.

50 Latch heads 39 are formed with annular lock grooves 46, the walls of which are at approximately a right angle to the axis of said latch heads. These grooves are arranged to be engaged by lock bolts 47 mounted for radial movements in the bearing rings 41 and, as shown, yieldingly pressed inward by curved springs 48 attached to the said lock bolts at one end, and at their other ends, attached to the said rings, as best shown in Fig. 3. When one of these lock bolts is engaged with the lock groove of the coöperating latch head, it will 55 positively lock the same and the plunger 36, and, consequently, the reflector and light bulb in predetermined positions.

60 For releasing the latches, I provide a magnetic trip which, as shown, is arranged 65 as follows:

A soft iron armature in the form of a lever 49 is pivoted to an arm 50 projected from one of the bearing rings 41. The free end of this armature lever 49 is perforated, or otherwise formed, so that it will clear the adjacent portion of the coöperating latch head 40, but will be subject, nevertheless, to the magnetic force of the adjacent solenoid. The lever 49 is provided with a wedge shaped lug 51, the point of which is normally in a position to engage between the free end of the spring 48 and the adjacent bearing ring 41. A light coiled spring 52 yieldingly holds the lever 49 toward the coöperating solenoid, but not with sufficient force to overcome the coöperating spring 48 and attached lock bolt 47.

Let it be assumed that normally the upper latch head 39 is so adjusted that the reflector 2 stands with its axis coincident with that of the casing 1 and the lamp bulb will stand with the hot portion of its filament at the axis of the said reflector. As will be understood, the filament of the bulb may be set at the focal center of the reflector 90 by axial adjustments of the lamp socket. These adjustments shown in Fig. 1 are, therefore, those which give the greatest light projection or longest light beams on the road ahead of the machine, as required 95 in traveling country roads. In such position, the reflector and lamp are positively held by the engagement of the upper lock bolt 47 with the groove 46 of the upper latch head 39.

100 For city traveling, and especially where city ordinances require dimmed or non-blinding lights, the reflector is oscillated vertically so that its axis is inclined downward ahead of the machine, and the light bulb is raised in respect to the axis of the reflector, so that the light beam will be projected onto the ground more closely in front of the machine. This adjustment of the said reflector and lamp will be produced whenever the upper solenoid 37 is energized. The first effect of this energizing of the said upper solenoid is to draw the upper tripping lever 49 downward, thereby causing its wedge lug 51 to retract the lock bolt 47 and release the plunger or magnetic core 36; and the second effect of the energizing said upper solenoid is to draw the plunger or magnetic core 36 upward and thereby, through the lever 34, 110 rocking the rear portion of the reflector upward on its pivots 2^a and rocking the light bulb and front portion of the lamp socket upward on the fulcrum ring 26. In this way, the axis of the reflector is inclined downward and the light bulb is raised to a greater extent than is the rear portion of the reflector, so that the filament of the bulb is then raised above the inclined axis of the reflector, so as to further increase the downward deflection of the light rays.

The extent to which the reflector will be rocked, may be varied by adjustments of the lower latch head 39, and the extent to which the light bulb will be raised in respect 5 to the axis of the reflector, may be varied by adjustments of the annular fulcrum 26 longitudinally of the lamp socket. The closer the fulcrum 26 is set to the pivotal connection between the lamp socket and reflector, 10 the greater will be the elevation given to the light bulb, and the converse of this statement is, of course, also true.

When the reflector and light bulb are raised, as just above stated, they will be 15 positively locked in such position by the engagement of the lower lock bolt 47 with the groove 46 of the lower latch head 39. To bring the said parts back to their normal positions shown in Fig. 1, the lower solenoid 20 37 is energized and the first effect thereof is, of course, to cause the wedge lock of the lower armature lever 49 to release the lower lock bolt 47 from the groove 46 of the lower latch head 39, and the second effect 25 is to cause the plunger or core 36 to move downward, thereby restoring the said parts to the position shown in Fig. 1.

What I claim is:

1. In a headlight, the combination with a 30 reflector, of a lamp therein pivotally supported for oscillations toward and from the axis of said reflector, and a lamp fulcrum adjustable toward and from the lamp pivot.

2. In a headlight, the combination with a 35 reflector, of a lamp support pivotally associated with said reflector and adapted to support a lamp within the reflector, and a fulcrum for the rear portion of said lamp support, mounted for adjustments toward 40 and from the pivot of said lamp support.

3. In a headlight, the combination with a reflector, of a lamp support pivotally connected thereto and adapted to support a lamp within said reflector, an annular fulcrum supporting and surrounding the rear 45 portion of said lamp support, and means for adjusting said fulcrum axially toward and from the pivot of said lamp support.

4. In a headlight, the combination with a 50 reflector mounted for oscillatory movements, of a lamp support pivoted to said reflector and adapted to support a lamp within said reflector.

5. In a headlight, the combination with a 55 reflector mounted for oscillatory movements, of a lamp support pivoted to said reflector and adapted to support a lamp within said reflector, and a fulcrum for the rear portion of said lamp holder, upon which the said 60 lamp support oscillates when moved with said reflector.

6. In a headlight, the combination with a reflector mounted for oscillatory movements, of a lamp support pivoted to said reflector 65 and adapted to support a lamp within said

reflector, and an annular fulcrum for the rear portion of said lamp support, mounted for axial adjustments toward and from the pivot of said lamp support.

7. In a headlight, the combination with a 70 reflector, of a lamp support having a pivotal connection to said reflector and having a relatively fixed fulcrum and adapted to support a lamp within said reflector, means for moving said lamp toward and from the axis 75 of said reflector, by the oscillatory movement of the said reflector.

8. In a headlight, the combination with a 80 casing, of a reflector pivoted thereto for vertical oscillatory movements, and a lamp support having a fulcrum within said casing at the rear of said reflector, pivotally connected to said reflector for vertical oscillatory movements therewith, and adapted to support a lamp within said reflector. 85

9. In a headlight, the combination with a 90 casing, of a reflector pivoted thereto for oscillatory movements, a lamp support pivoted to said reflector and adapted to support a lamp within the reflector, a fulcrum for the rear portion of said lamp support, located within said casing back of said reflector, and means operative through the back of said reflector for adjusting said fulcrum longitudinally of the axis of said reflector. 95

10. In a headlight, the combination with a 100 casing, of a reflector pivoted thereto for oscillatory movements, a lamp support pivoted to said reflector and adapted to support a lamp within the reflector, a fulcrum for the rear portion of said lamp support, located within said casing back of said reflector, and means operative through the back of said reflector for adjusting said fulcrum longitudinally of the axis of said reflector, the said 105 adjusting means comprising a rotary member having a sliding engagement with the said fulcrum.

11. In a headlight, the combination with a 110 casing and a reflector supported thereby, of a lamp support within said casing, mounted for oscillatory movements and provided with an axially adjustable lamp holder adapted to support a lamp within said reflector, a fulcrum for the rear portion of said lamp holder, and two adjusting devices extending through the back of said reflector, the one operative to adjust said fulcrum longitudinally of the axis of said reflector, and the other operative to adjust said lamp holder 115 axially of said lamp support. 120

12. In a headlight, the combination with a reflector and a lamp support, one of which members is capable of oscillatory movement in respect to the other, of a plunger movable 125 to oscillate said oscillatory member, positive locks for limiting the movements of said plunger and holding the same in extreme positions, and automatic releasing devices for the said locks. 130

13. In a headlight, the combination with a reflector and a lamp support, one of which members is capable of oscillatory movement in respect to the other, of a plunger for moving the oscillatory member, electro-magnetic devices for reciprocating said plunger, positive locks for limiting the movements of said plunger and holding the same in extreme po-

sitions, and magnetically operated releasing devices for said locks.

10

In testimony whereof I affix my signature in presence of two witnesses.

OVERTON WINSTON.
